UNITED STATES PATENT OFFICE.

HOWARD R. LOUGHRIFFE, OF CASTLE SHANNON, PENNSYLVANIA.

BUILDING BLOCK.

Application filed June 24, 1927. Serial No. 201,113.

My invention refers to improvements in concrete building blocks for walls and similar constructions.

It has for its object to provide a block of 5 novel construction, adapting it to firm incorporation with other blocks by reason of interfitting and co-operating ridge and channel portions and registering perforating openings for anchoring connection by intervening 10 anchoring or cementing portions in the manner of binders.

The invention also provides for correct and easy placement of the blocks in buildings, facilitating proper placement and relationship, while also providing against accidental 15 displacement of the blocks in a wall.

A further material advantage and improvement is in the close contacting engagement between the outer edge portions of adjacent blocks, providing for continuous 20 smooth exterior and interior surfaces, together with other features of construction and advantage, as hereinafter described.

Referring to the drawings, showing certain 25 preferred embodiments of the invention:

Fig. 1 is a perspective view of one form of the block, showing its under side;

Fig. 2 is a similar view, showing the upper 30 face of a block adapted for corner construction with the block of Fig. 1;

Fig. 3 is a plan view, showing the corner portion of a wall laid with said blocks;

Fig. 4 is a vertical sectional view on the line IV—IV of Fig. 3;

Fig. 5 is a partial detail view of the end of 35 the block, with the grooves blanked;

Fig. 6 is a cross sectional view on the line VI—VI of Fig. 3, showing the joint;

Fig. 7 is a similar view, showing a modified 40 construction;

Fig. 8 is a longitudinal part sectional elevation, showing the standard side wall block, on the line VIII—VIII of Fig. 10;

Fig. 9 is an end view of Fig. 8;

Fig. 10 is a plan view of Fig. 8;

Fig. 11 is an under plan view of a double 45 rib block used in forming the joint structure of Fig. 7;

Fig. 12 is a detail plan view, showing a 50 modified construction.

The block as a whole is preferably of standard dimensions, as 8 in. x 8 in. x 16 in., and is made in the usual way of manufacturing such articles, utilizing any suitable aggregate and binder. Similar sizes, as half blocks for

corners, filling pieces around openings, etc., made in fractional multiples of a full sized block, may, of course, be made and adapted to interfit and co-ordinate with the standard block, as will be readily understood by those skilled in the art.

The block A is usually provided with one or more centrally arranged openings A extending from top to bottom, preferably slightly tapered for easy removal from the forming 65 cores of the block-forming press. Endmost channels 2 extend across one or both ends of the blocks for matching completion of a full sized opening, when the blocks are placed end to end in the wall in erection.

Similar matching openings 3 or 3^a are preferably also provided at opposite sides of the middle opening 3, whereby to provide circulating ventilating apertures, with main 70 openings A, throughout the vertical interior 75 of the completed wall. If desired, these openings may be also used to interlock the blocks against lateral movement, by a filling of concrete. Openings 2, 3 and 3^a, like openings a, are formed by the usual cores of the block- 80 forming press.

When it is desired to make a solid end block, as at 4, Fig. 5, the cores for forming end 85 openings 2, 3 or 3^a may be removed at one end of the machine, resulting in a continuous, 90 solid end wall, as will be readily understood.

One side, as the top, of the block is provided with longitudinal gutters or channels 5 inwardly of the bearing or supporting edge portions 6. The opposite side of the block 90 is provided with co-operating longitudinal ribs 7 inwardly of corresponding contacting supporting edges 8.

Channels 5 are sufficiently deeper than 95 ridges 7 to provide for intervening space for the grouting or cementing body 9, which fills the intervening space between the bearing edges 6, 8, and the interior middle portion of the blocks, as in Fig. 6.

The upper middle surface of the blocks is 100 flat, as at 10, approximately on the same general level as the upper bearing edges 6, while the corresponding lower face of the block 11 is upwardly arched, providing a considerable intervening space 12. Such space, extending 105 longitudinally between the blocks and in open communication with spaces a, provides for ample ventilating channel construction in the erected wall. Such space under the blocks also provides ample clearance for any 110

excess grouting material in the block, above the level of the bearing edges 6, should the middle portion of the block extend above such surfaces.

5. Ordinarily, such longitudinal channels, ridges and edge bearing portions are sufficient for an ordinary main wall block between its ends.

10 In blocks designed for corner constructions, as in Figs. 1 and 2, the same general features are embodied. One end portion of the block, however, is continuously flat and closed, as at 4, with a supplemental filling 13, closing the channel 12 at one end, at the 15 lower end portion of the block, and, if desired, with fillings 14 at the upper corresponding end, closing the longitudinal channels 5. Otherwise, as in Fig. 2, the longitudinal channels may run clear to the end, the 20 terminal openings of the channels being filled with mortar in building the wall.

In such corner blocks they are provided with transverse channels 5^a, extending across the end and inner portion of the block, for 25 interfitting engagement therewith of corresponding downwardly extending ribs 7^a, extending across between the longitudinal ribs 7, as in Fig. 1.

Ribs 7^a merge into the middle bottom recessed portion by reinforcing thicker or 30 merely concaved fillet portions 15, and as shown the grooves 5 and 5^a cross each other and also cut through the side and end bearing edges 6 and 6^a respectively, as in Fig. 2.

35 As thus constructed it will be seen that in laying up a wall, the corner construction provides for a positive interlock, with absolute certainty of flush continuation with outside surfaces, and close bearing contact of edges 40 6 and 8.

In the same manner the ends of the blocks abut against each other, forming flush continuations of the surfaces, as at 16, Fig. 3.

With the intervening grouting 9 there is 45 provided a strong anchoring connection between the blocks, holding them firmly together, while the interengaging shoulder and channel construction fixedly locates the blocks with relation to each other against lateral shifting, either longitudinally or laterally.

50 In Fig. 7 I show a modified construction in which the ribs are doubled, as at 7^b, with an intervening recess 7^c. When laid upon the lower block and filled with the grouting 9, there is a double rib engagement therein, in 55 addition to the interlocking function between the ribs and grooves, greatly increasing the surface contact with the binder and further increasing the holding effect.

60 The construction of my improved block, in either of the forms described, will be readily understood and appreciated by all those familiar with this class of building material. Whether used for a bare wall, or with an 65 inner or outer coating of plaster, stucco or

the like, or both, the resulting wall is solid, substantial, and continuously smooth as to the block surfaces.

The positive bearing of one block against the other insures solidity and strength, with ample closeness and connection due to the grouting and omission of any mortar whatever on either outer face of the block. The sealing of the ends in the manner described insures smooth continuity at the corners, 75 while the provision for air circulation through the various openings is in conformity with the best recognized practice in concrete masonry wall construction.

This application is a continuation and division in part of my prior application filed October 27, 1926, Serial No. 144,483.

Having described my invention, what I claim is:

1. A building block having longitudinal 85 grooves along its upper side edge portions and longitudinal ribs along its lower side edge portions for interfitting engagement with the grooves of an adjacent block, and provided with endmost grooves coincident 90 with the longitudinal grooves and ribs, the inner faces of the ribs being extended upwardly beyond their main body portions providing interior clearance.

2. A building block having longitudinal 95 grooves along its upper side edge portions and outer bearing faces and longitudinal ribs along and inwardly of its lower side edge portions for interfitting engagement with the grooves of an adjacent block and a middle intervening upwardly recessed channel formed by extending the inner faces of the ribs upwardly and inwardly beyond the side edge portions of the block.

3. A building block having longitudinal 105 grooves along its upper side edge portions, transverse grooves intersecting said grooves, and corresponding longitudinal and transverse ribs along its lower side edge portions and for interfitting engagement with similarly arranged grooves of an adjacent block, 110 the inner faces of the longitudinal ribs extending upwardly beyond the plane of the side edges.

4. A building block having longitudinal 115 grooves along its upper side edge portions and longitudinal ribs along its lower side edge portions for interfitting engagement with the grooves of an adjacent block, the inner portion of the ribs being concaved and providing 120 clearance above the plane of the outer contacting edge portions.

5. A building block having longitudinal 125 grooves along its upper side edge portions and longitudinal ribs along its lower side edge portions for interfitting engagement with the grooves of an adjacent block with intervening inwardly open clearance for plastic binder material when the side edge portions are in contact.

6. A building block having longitudinal grooves along its upper side edge portions and longitudinal ribs along its lower side edge portions, and outer flat bearing faces beyond the grooves and ribs adapting one block to be supported in direct contact with the outer side edge portion of an adjacent block, with continuously open binder clearance between the ribs and grooves at their inner portions.
- 10 7. A building block having longitudinal grooves along its upper side edge portions and longitudinal ribs along its lower side edge portions for interfitting engagement with the grooves of an adjacent block, with transverse grooves across the ends of the block in the plane of said grooves and ribs, said ribs merging into upwardly concaved surfaces providing continuously open clearance for intervening binding material.
- 20 8. A building block having longitudinal grooves along its upper side edge portions and plural member ribs along its lower side edge portions for interfitting engagement with the grooves of an adjacent block, the innermost of said ribs merging into upwardly concaved surfaces providing continuously open clearance for intervening binding material.
- 25 9. In combination, a lower block having directly contacting edge bearing portions, a groove inwardly of said bearing portion, an upper block having a co-acting directly contacting edge bearing portion and a rib inwardly thereof with its inner surface receding upwardly beyond the plane of the edge bearing portion for engagement of said groove and an intervening binder.
- 30 10. In combination, a building block having on its top outer edge bearing faces and grooves inwardly thereof, a superimposed block having on its bottom outer contacting
- edge bearing faces and ribs inwardly thereof with intervening continuous clearance inwardly beyond the edge bearing faces, and a binding filler of suitable plastic material between the grooves and ribs closing the space inwardly of the bearing faces for a portion of the clearance.
- 35 11. In combination, a building block having on its top outer edge bearing faces and grooves inwardly thereof, a superimposed block having on its bottom outer contacting edge bearing faces and series of plural ribs inwardly thereof with intervening continuous clearance inwardly beyond the edge bearing faces, and a binding filler of suitable plastic material between the grooves and ribs closing the space inwardly of the bearing faces for a portion of the clearance.
- 40 12. A building block having an outer upper and lower flat side edge bearing face, an adjacent groove along one face of the block, and a correspondingly located rib along its other face, the inner surface of the rib receding inwardly and upwardly beyond the plane of the flat side edge providing clearance space between it and the inner portion of the groove of an adjacent block.
- 45 13. In combination, a lower block having a longitudinal groove along its upper face and an outer flat bearing strip surface, and a superimposed block having a co-acting longitudinal rib along its under face and an outer flat bearing strip surface in direct contact with said surface, and an intervening binder between the groove and rib extending inwardly above the plane of the bearing surfaces.
- 50 55 60 65 70 75 In testimony whereof I hereunto affix my signature.
- HOWARD R. LOUGHridge.
